TICKET PUNCHING AND STAMPING MACHINE

Eugene Hugh Healy, Vineland, N. J.

Application June 8, 1934, Serial No. 729,706

5 Claims. (Cl. 101—66)

The invention relates to a ticket handling machine and more especially to a ticket punching and stamping machine.

The primary object of the invention is the provision of a machine of this character, wherein a transportation ticket will be punched and stamped when issued to a passenger so as to identify the starting and destination point of such passenger, as well as the nature of the trip, either one trip, round trip or several one-way trips, the ticket being also stamped to indicate the time of issuance thereof, the said issued ticket being deposited within the machine, while delivered to the passenger is a duplicate except the stamping thereof of the time of issuance and thus in this manner a bus owner or owners will be enabled to check up on their drivers to ascertain whether or not a driver is issuing shorter distance tickets and charging the full distance that the passenger rides and then keeping the difference in the price of such irregular issue of tickets.

Another object of the invention is the provision of a machine of this character, wherein twin tickets are automatically fed within the machine and these punched for identifying the destination and starting points of a passenger in transit, one ticket being delivered or issued to the passenger and the other ticket retained within the machine so that a complete record may be had of the passengers traveling upon a bus or other transportation medium, the deposited ticket being stamped to indicate the time of issuance of the other ticket so that a complete record may be had of each ticket issued by the machine, the latter being manually controlled.

A further object of the invention is the provision of a machine of this character, wherein the construction thereof is novel in its entirety and the aggroupment of the elements is such as to render the machine compact and for manual control by a driver or operator of a transportation vehicle.

A still further object of the invention is the provision of a machine of this character which is extremely simple in its construction and assembly, thoroughly reliable and efficient in its operation, effective for the purposes intended thereof, readily and easily operated with dispatch, requiring but a single operator, automatic in the handling of the tickets, strong, durable, and inexpensive to manufacture.

With these and other objects in view, the invention consists in the features of construction, combination and arrangement of parts as will be hereinafter more fully described in detail, illustrated in the accompanying drawings, which dis-

close the preferred embodiment of the invention, and pointed out in the claims hereunto appended.

In the accompanying drawings:

Figure 1 is a vertical longitudinal sectional view through a machine constructed in accordance with the invention, the parts being in normal starting position.

Figure 2 is a sectional view on the line 2—2 of Figure 1 looking in the direction of the arrows.

Figure 3 is a sectional view on the line 3—3 of Figure 1 looking in the direction of the arrows.

Figure 4 is a sectional view on the line 4—4 of Figure 1 looking in the direction of the arrow.

Figure 5 is a vertical transverse sectional view showing in detail the manner of depositing a 15 ticket within the machine.

Figure 6 is a sectional view on the line 6—6 of Figure 1 looking in the direction of the arrows.

Figure 7 is a sectional view on the line 7—7 of Figure 1 looking in the direction of the arrows. Figure 8 is a fragmentary top plan view show-

ing the ticket markings and the scale identifier therefor.

Similar reference characters indicate corresponding parts throughout the several views in

Referring to the drawings in detail, the machine comprises a stand-supported casing 10 having rising from its base 11 a support 12 for rolled ticket strips 13 and 14, respectively, the rolls being fitted upon journals 15 in the support 12. These strips 13 and 14 are printed or otherwise marked upon their upper faces with transportation indicia 16 and 17, respectively, as for example, stations along a determined route, and the nature of the trip en route, for example, a single one-way trip, a return trip, a pass, a transfer or several trips, and the indicia 16 and 17 appear in repeating fashion throughout the extent of the strips so as to divide the said strips into a series of tickets. It is, of course, understood that the character of the indicia 16 and 17 upon the strips 13 and 14 may be varied according to requirements and congruous with the character of transportation and routing of the same. It is to be understood that the indicia 16 and 17 is duplicated on the respective strips 13 and 14 so that one ticket may be issued to a passenger and the other ticket deposited in the machine for checking up purposes of such ticket issuance.

Arranged within the casing 10 and builded upon 55

its base 11 is a suitable frame 18 in which is disposed a horizontal punching bed 19 upon which travel, in their superimposed relation, the strips 13 and 14 as fed between guide rollers 20 suitably journaled in the frame. Above the bed 19, within a head 21, are vertically disposed rows of punches 22, these being uniformly spaced apart in the respective rows and opposite each other in longitudinal disposition of the machine at opposite sides of the longitudinal center of the same. The punches 22 are normally lifted above the bed 19 by coiled springs 23, these tensioning said punches when depressed in the punching operation of the machine.

15 The head 21 is fitted with a plate 24, the grooves 25 in its upper side aligning with the rows of punches 22, and formed in this plate to open through the bottoms of the grooves 25 are vertical slots 26 for actuator pins 27, these being slidably fitted in guide barrels 28 extended within the grooves 25 and upon arms 29 of setting slides 30 movably supported upon guide rods 31 arranged in the frame 18. The slots 26 constitute clearances for the actuator pins 27 so that these may be brought into vertical alignment with selected punches 22 for the operation of the same. The pins 27 are selectively aligned with the punches 22 on the shifting of the slides 30 so that when the pins 27 are actuated the punches 22 will punch the strips 13 and 14 when upon the bed 19.

35 The slides 31 have connected therewith shift rods 32, these being extended outside of the casing 10 and carrying hand knobs 33 at their outer ends for manual manipulation thereof. Rising from the slides 30 are pointers 34, these being extended through suitable slots 35 in the top of the casing 10 to coat with a setting scale 36 upon said top and the identifying indicia 16 and 40 17 of charts 37 duplicating the indicia present upon the ticket sections 38 of the strips 13 and 14.

45 Horizontally journaled in the head 21 above the actuator pins 27 are eccentrics 39, these being active upon the said pins 27 to move the same for the operation of the selected punches 22. Carried by the journals of said eccentrics 39 are gears 40, these meshing with a double gear 41 which also meshes with a gear 42 upon a driven shaft 43 journaled in the frame 18. This shaft 50 43 carries one of a train of gears 44, these being mounted outside of the frame 18 within the casing 10 and driven from a pinion 45 on a power shaft 46 fitted with a hand crank 47, manually controlled.

55 Supported for vertical sliding movement in the frame 18 is a lifter and guide track 48 for a catch pin 49 slidably fitted in a carrier 50 movable upon a horizontal guide rod 51 mounted in said frame 18, the pin 49 being tensioned by 60 a spring 52 which holds the said pin in contact with the track 48 and below the path of travel of the strips 13 and 14 upon the bed 19 when the said track 48 is in its lowered position. On the raising of the track 48 the pin 49 is projected upwardly to engage in openings 53 formed at intervals in the strips 13 and 14. This carrier 50 is shifted upon the rod 51 by a throw lever 54 pivoted at 55 in the frame 18, the upper end of the lever 54 being forked at 56 to 65 engage a coupling lug 57 on said carrier 50. The lever 54 has pivoted thereto a link 58, the same being pivoted to a throw arm 59 pivoted at 60 in the frame 18, the arm 59 being fitted with a roller 61 contacting with an eccentric 62 driven 70 from another of the train of gears 44 so that the

catch pin 49 is shifted by the carrier 50 upon the rod 51 to advance the strips 13 and 14 the distance of a ticket section 38 after the punching of such section.

5 The lifter and guide track 48 is held for vertical movement by suitable guides 63 and is operated upon by a lifting cam 64 driven from another of the train of gears 44 so that the pin 49 will be projected by the track 48 to engage in the openings 53 in the several strips 13 and 14 for the advancement thereof the length of a ticket section 38 of such strips.

Upon the shaft carrying the cam 64 is a trip 65 operating a bell striker 66 pivoted at 67 for sounding a bell 68 for signalling purposes to be 15 indicative of the advancement of the strips 13 and 14 the distance of the length of a ticket section 38 of such strips.

The shaft carrying the cam 64 and trip 65 also carries an eccentric 69 which operates to 20 rock an arm 70 pivoted at 71 intermediate of its length. This arm 70 has pivoted thereto the links 72 connected to a blade holder 73 slidably supported upon vertical posts 74 and carrying the shearing blade 75 having the beveled angular cutting edge 76 for shearing the strips 13 and 14 in unison when the same have moved the length of a ticket section 38 and the latter brought into position in duplicate with relation to a stamping bed 77, one ticket section, that is 30 to say, the uppermost one, riding upon this bed and the other coming into position below the bed for the stamping thereof by a stamping time clock 78 of any approved type. The clock 78 is supported for movement to stamping position by uprights 79 through the medium of a cushioning device 80 operated upon by a roller 81 carried by an actuating arm 82 pivoted at 83 and controlled in its movement by an eccentric 84 carried upon the shaft having the eccentric 62. 40

Beneath the bed 77 is a delivery shelf 85 upon which falls the ticket section 38 after the stamping thereof and this shelf has the laterally inclined discharge end portion 86 overhanging a ticket section receiver or depository 87 within the 45 casing 10 so that the ticket section dropped upon the shelf 85 will be delivered to said receptacle or depository 87 through the action of a kicker 88 pivoted at 89 and operated by a tripping pin 90 active upon the tail piece 91 50 of said kicker, the pin 90 being carried by the clock 78 and controlled thereby.

The clock mechanism of the clock 78 is set and wound in any desirable manner and its time stamping mechanism is inked in any suitable 55 way, the stamping time clock being of conventional type and constituting no part of the present invention except for the stamping of a ticket section of the time of issue of the original ticket section to a purchaser, the time stamped duplicate ticket section being delivered into the machine and retained thereby, while the original ticket section is removed from the bed 77 by its purchaser, this section being devoid of time 60 stamping, as will be apparent.

Upon the gear 44 of the train operating the shaft 43 is a tripping lug 92 actuating the trigger 93 of a counting register 94, the latter being of any suitable type to register successively the 70 number of ticket sections 38 punched and stamped in the operation of the machine and this register being visible for inspection without the casing 10.

The receptacle or depository 87 is preferably 75

- carried by a removable door or section 95 of the casing 10 so that access may be had to the receptacle or depository for the acquiring of the ticket sections deposited or delivered thereto.
- 5 The angular disposition of the cutting edge 76 of the blade 75 assures a positive shearing of the strips 13 and 14 for the severance of the ticket section 38 therefrom subsequent to the punching and stamping of these sections.
- 10 The location of the stamping bed 77 is at the delivery end 96 of the casing 10 where the original issued ticket sections 38 are accessible and acquired by the purchaser. This bed 77 tapers at 97 in the direction of the punching bed and functions to separate the duplicate ticket sections, one passing unto the bed and the other beneath the same into stamping position. The ticket section passed upon the bed is the one acquired by the purchaser.
- 15 It should be apparent that the mechanism of the machine is timed so that there will be required three revolutions of the hand-crank 47 for the punching of duplicate ticket sections 38 of the strips 13 and 14, the severing of these sections from the strips and the stamping of the time of issuance of one section and its deposit in the machine with the other section exposed and free at the delivery end 96 for the acquiring thereof by the purchaser of a ticket.
- 20 The operator of the machine, by the shift rods 32, can support actuator pins 27 for the selective working of punches 22, whereby these automatically will punch duplicate ticket sections 38 of the strips 13 and 14 to identify the data 16 and 35 17 appearing upon such sections as indicative of the starting and stopping points of a route and the nature of the ticket section purchased, that is, a single trip, a return trip, a paid trip, a pass, transfer, half-fare, inbound or outbound, or in 40 other words, the value of the issuance of such ticket section.
- It should be apparent that a positive and complete check can be had upon the operator of a transportation vehicle as to the ticket issuance, the time of issuance thereof and the value of such issuance as a duplicate of the purchased ticket and the time of issuance thereof stamped upon the duplicate as acquired by a purchaser or passenger of such vehicle will be deposited within 45 the machine and constitute a check on the operator of such machine.
- What is claimed is:
1. A machine of the character described comprising a series of data punches, manually movable actuator pins for said punches and selectively movable with relation to the latter, plural ticket strips movable simultaneously into the path of the punches to be punched thereby, means for feeding the strips simultaneously, means for severing the strips subsequent to the punching, means for advancing the punched strips simultaneously with each other the length of a ticket section prior to severing of said strips, and time stamping mechanism movable for stamping 50 one of the severed strip sections.
2. A machine of the character described comprising a series of data punches, manually movable actuator pins for said punches and selectively movable with relation to the latter, plural ticket strips movable simultaneously into the path of the punches to be punched thereby, means for feeding the strips simultaneously, means for severing the strips subsequent to the punching, means for advancing the punched strips simultaneously with each other the length of a ticket section prior to severing of said strips, time stamping mechanism movable for stamping one of the severed strip sections, and mechanism for actuating said stamping mechanism.
3. A machine of the character described comprising a series of data punches, manually movable actuator pins for said punches and selectively movable with relation to the latter, plural ticket strips movable simultaneously into the path of the punches to be punched thereby, means for feeding the strips simultaneously, means for severing the strips subsequent to the punching, means for advancing the punched strips simultaneously with each other the length of a ticket section prior to severing of said strips, time stamping mechanism movable for stamping one of the severed strip sections, mechanism for actuating said stamping mechanism, and means for depositing the stamped strip section.
4. A machine of the character described comprising a series of data punches, manually movable actuator pins for said punches and selectively movable with relation to the latter, plural ticket strips movable simultaneously into the path of the punches to be punched thereby, means for feeding the strips simultaneously, means for severing the strips subsequent to the punching, means for advancing the punched strips simultaneously with each other the length of a ticket section prior to severing of said strips, time stamping mechanism movable for stamping one of the severed strip sections, mechanism for actuating said stamping mechanism, means for depositing the stamped strip section, and cushioning means for said stamping mechanism.
5. A machine of the character described comprising a series of data punches, manually movable actuator pins for said punches and selectively movable with relation to the latter, plural ticket strips movable simultaneously into the path of the punches to be punched thereby, means for feeding the strips simultaneously, means for severing the strips subsequent to the punching, means for advancing the punched strips simultaneously with each other the length of a ticket section prior to severing of said strips, time stamping mechanism movable for stamping one of the severed strip sections, mechanism for actuating said stamping mechanism, means for depositing the stamped strip section, cushioning means for said stamping mechanism, and manually controlled timed mechanism actuating the said means and last-named mechanism.
